UNITED STATES PATENT OFFICE.

REINHOLD H. GRIPP AND JOSEPH PYGEORGE, OF OAKLAND, CALIFORNIA.

SOAP-CASTING MACHINE.

Application filed November 28, 1919, Serial No. 341,250.

To all whom it may concern:

Be it known that we, REINHOLD H. GRIPP and JOSEPH PYGEORGE, citizens of the United States, residing at Oakland, in the county 5 of Alameda and State of California, have invented certain new and useful Improvements in Soap-Casting Machines, of which the following is a specification.

Our invention is a soap casting machine 10 for automatically casting soap into cakes.

Referring to the annexed drawings which form a part of this specification:

Figure 1 is a side elevation of our invention.

Figure 2 is an end elevation of our invention.

Figure 3 is a plan view of a portion of one end of our invention.

Figure 4 is a cross section of our invention taken on line 4—4 of Figure 1.

Figure 5 is a side elevation of the soap pump.

Figure 6 is a side elevation of the soap pump taken from the opposite side from 25 which Figure 5 is taken.

Figure 7 is an end elevation of the soap pump.

Figure 8 is a sectional view of the soap pump taken on line 8—8 of Figure 7.

Figure 9 is a side elevation of the soap mold.

Figure 10 is an end elevation of the soap mold.

Figure 11 is a longitudinal section of the soap mold taken on line 11—11 of Figure 10.

Figure 12 is a section on line 12—12 of Figure 5.

In the drawings 1 indicates the frame of 40 the machine which includes an intermediate section 2 and end sections 3 and 4. A shaft 5 is journaled in bearings 6 on the frame section 3, which shaft carries two sprockets 7—7. A shaft 8 journaled in bearings 9 45 on the frame section 4 carries two sprockets 10—10. Over each sprocket 7 and a sprocket 10 extend chains 11—11 respectively. On the chains 11—11 at suitable intervals are mounted soap molds 12. Each mold includes 50 a rectangular box-shaped mold receptacle 13 in the form of a soap cake, a mold frame 14 and a mold plunger 15. The frame 14 is formed with a lower transverse member 16, and side members 17—17 between and to 55 which side members the mold receptacle 12 is detachably secured by means of screws 18.

On each of said side frame members 17 at the ends thereof are formed bearings 19—19 from which trunnions 20—20 extend laterally through the bearings of upstanding links 21—21 on the chains 11. The links 21 at the rear end of the molds 12 are formed with elongated rearwardly extending bearings 22 through which the rear trunnions 20 of the mold extend, which bearings allow said trunnions to move rearwardly therein to enable the chains 11 to carry the mold around the sprockets 7 and 10. A rod 25 extends from the plunger 15 in each mold through an aperture 26 in the bottom of the 70 mold and through a bearing 27 in the lower frame member 16. A spring 28 surrounds each rod 25 between the lower frame member 16 and a head 29 on the end of the rod, which spring holds the plunger 15 75 against the bottom of the mold receptacle 13. The upper reach of the chains 11 travel through a refrigerating tunnel 30 mounted in the upper part of the intermediate frame section 2, in which tunnel is a refrigeration 80 coil 31. The lower reach of the chains 11 travel through a refrigeration tunnel 32 mounted in the lower part of frame section 2, said tunnel being provided with a refrigeration coil 33. Inside the tunnel 30 are 85 mounted rails 34 upon which the chains 11 travel through said tunnel and are maintained horizontal against sagging under the weight of the soap in the molds. A shaft 35 journaled in bearings 36 on the frame 3 90 carries a pulley 37 and sprockets 38 and 39. A sprocket 40 is secured on the shaft 5 in alignment with sprocket 38 over which sprockets travels a chain 41 whereby the shaft 5 and the chains 11—11 are driven. 95

Near one end of the machine above the frame sections 2 and 3 is mounted a container 50 in which is placed liquid soap. Said container has an outlet 51 in the bottom thereof which leads into a soap pump 52 100 mounted on the bottom of the container, a flange 53 being formed around the said outlet to which a flange 54 around the pump inlet 55 is bolted by bolts 56. Said pump has a horizontal cylinder 57 in which reciprocates a piston 58. The pump has a duct 59 and a port 60 leading from inlet 55 into said duct, the duct leading from said port into one end of the cylinder 57. A valve 61 controls the admission of soap from inlet 55 110 into the duct 59, the stem 62 of said valve extending through a bearing 63 and a pack-

ing box 64 in the pump casing. On the outer end of the valve stem a collar 65 is pinned by a pin 66. A spring 67 surrounds the stem 62 between the packing box 64 and 5 the collar 65, said spring normally holding valve 61 closed and preventing the liquid soap from flowing into the pump. The pump casing has a socket bearing 70 below the same end of the cylinder 57 into which 10 the duct 59 leads, and with a duct 71 leading from said end of the cylinder into said socket bearing. On the upper end of a spout 75 is formed a hollow journal 76 which fits in socket bearing 70. Said bearing is made in 15 two parts 77 and 78, the part 77 being formed on the pump casing and the part 77 being bolted to part 78 by bolts 79 which extend through a flange 80 on part 78 and screw into a flange 81 on the part 77. The part 78 has 20 a slot 82 through which the spout 75 extends, said slot being long enough to allow the spout to oscillate forwardly and backwardly with relation to the chains 11. The journal 76 has an opening 83 in its upper wall which 25 registers with duct 71 and admits liquid soap from the cylinder 57 into the journal and spout 75. A nozzle 80 screws onto the lower end of spout 75, said nozzle being formed with an inlet duct 81 with which the spout 30 75 communicates, an outlet duct 82 and a port 83' leading from said inlet into said outlet. A valve 85 controls port 83, the stem 86 of said valve extending laterally from the nozzle through a bearing 87 formed in the wall 35 of the nozzle. A collar 88 is pinned on the outer end of stem 86 by a pin 89. A spring 90 which surrounds said stem between the bearing 87 and collar 88 normally closes the valve 85. A plug 91 is screwed in an opening 92 in the wall of the nozzle 80 opposite 40 valve 85, through which opening the valve may be inserted or removed when the plug is removed. A plug 93 is screwed in an opening 94 in the wall of the pump opposite 45 the valve 61, through which opening said valve may be inserted or removed when the plug is removed. To the outer end of the cylinder 57 is bolted a head 95 in which is a bearing 96 through which extends a piston 50 rod 97 to which the piston 58 is connected. A frame 98 extends from the head 95 and has a bearing 99 in its outer end through which also the piston rod 97 extends. A collar 100 is secured on the piston rod 97 from which 55 collar projects a pin 101. In a bearing 102 on the pump 52 is journaled a shaft 103 on one end of which is secured a disk 104. A pitman 105 is pivotally connected to disk 104 by a crank pin 106 and to the piston rod 97 by 60 pin 101 and collar 100. On the shaft 103 are also secured a sprocket 107 and a disk 108. A chain 109 travels over sprockets 107 and 39. A lever 110 is pivoted by a pin 111 on an arm 112 depending from the bearing 102, 65 said lever being provided at one side of its pivot with a longitudinal slot 113' through which extends and in which slides a pin 113 on the disk 108. The lower end of said lever is connected to one end of a link 114, the other end of which link is pivoted by a pin 70 115 to a clamp 116 on the spout 75.

On the frame section 2 before the entrance to the tunnel 32 is a cam 120. A chute 121 extends from a point below the cam 120.

The operation of our invention is as follows:

The chains 11 are driven in the direction of arrow (see Fig. 1) through the medium of sprockets 7, shaft 5, sprocket 40, chain 41, sprocket 38, shaft 35 and pulley 37 to which 80 power is applied. The piston 58 is reciprocated through the medium of sprocket 39, chain 109, sprocket 107, shaft 103, disk 104, pitman 105 and piston rod 97, while the spout 75 is oscillated through the medium of 85 sprocket 39, chain 109, sprocket 107, shaft 103, disk 108, lever 110 and link 114. As the piston 58 is drawn outwardly the valve 61 is opened and a charge of liquid soap, equal to the capacity of a mold 12, is drawn from the 90 container 50 into the cylinder 57 through inlet 55, port 60, and duct 59, while the spout 75 is swung backwardly directly over a mold 12 which has arrived at the top of sprockets 7. As said mold travels forwardly the piston 58 is moved inwardly; the valve 61 is closed; and the charge of liquid soap is forced out of the cylinder 57 through duct 71, opening 83, journal 76, spout 75 and nozzle 80, (the valve 85 opening to permit the 100 soap to pass through inlet 81, port 83' and outlet 82), into said mold, filling the mold, (the spout swinging forwardly with the mold and remaining directly over it while discharging the soap therein). When the 105 molds are filled with the liquid soap they are carried through the tunnel 30 in which the soap is cooled and hardened in the mold. As each mold comes under the cam 120 the head 29 at the end of piston rod 25 engages said 110 cam, which forces the piston 15 downward and the cake of soap, which has hardened and formed, out of the mold onto the conveyor 121, which conveys the cakes of soap to a suitable place of discharge where it discharges them. The molds 12 are further cooled as they pass through tunnel 32.

The molds after passing through the tunnel 32 are chilled so that when the soap is poured therein and passes through tunnel 30 120 and hardens it shrinks and is easily ejected from the mold without cracking.

The disk 104 is provided with a plurality of holes 130, 131 and 132 in which the pin 106 may be placed, said holes being 125 located at different distances from the center of the disk to give different strokes to the piston 58 to vary the charge in the pump and the size of the soap cake. The pin 106 is formed with a journal 133 and 130

a flange 134 on its outer end on which the pitman 105 is hung, said journal being of greater diameter than the rest of the pin and providing a shoulder 135 which engages 5 the outer face of the disk. The inner end of the pin is threaded to receive a nut 136 which engages a washer 137 on the pin against the rear face of the disk and draws the shoulders 135 against the outer face of 10 the disk.

Having described our invention, we claim:

1. A machine for casting soap including a conveyor, soap molds mounted on said conveyor, a soap pump, a swinging nozzle 15 on said pump, automatic means for actuating said pump to pump liquid soap through said nozzle, means for swinging said nozzle so as to follow each mold on the moving conveyor until it delivers enough soap to 20 fill the mold, and means for removing the molded soap cakes from the mold.

2. A machine for casting soap including a conveyor, soap molds on said conveyor, a soap pump for pumping a charge of liquid 25 soap equal to the capacity of a mold, a swinging nozzle on said pump, automatic means for actuating said pump to pump the charge of soap through said nozzle, means for swinging said nozzle so as to follow each mold on the moving conveyor until 30 it has delivered the full charge of soap into the mold, and means for removing the molded soap cakes from the molds.

3. A machine for casting soap into cakes 35 including an endless chain conveyor, soap molds on said conveyor, means for filling said molds with liquid soap, a refrigerating tunnel through which the conveyor and molds pass for cooling and hardening the 40 soap in the molds, means for ejecting the cakes of soap from the molds, and a refrigerating tunnel through which the conveyor and molds pass after the cakes of soap are

ejected from the molds for chilling the 45 molds.

4. A machine of the character disclosed including a plurality of molds, a soap pump for delivering its charge of liquid soap in said moulds, respectively, means for varying the stroke of the piston of said pump the 50 charge of the pump and the size of the soap cake cast in the mould, and means for removing the soap cakes from the moulds.

5. In a machine of the character disclosed, a conveyor, a plurality of soap 55 moulds on said conveyor, a soap pump including a disk provided with a plurality of holes at different distances from its center, a pitman connected at one end to the pump piston, a connecting pin adapted to extend 60 through any hole in said disk to connect the other end of said pitman to the disk to determine the stroke of the piston, a nozzle on said pump, and means for rotating said disk to cause the pump to deliver soap 65 through its nozzle into said moulds.

6. In a machine of the character disclosed, a conveyor, a plurality of soap moulds on said conveyor, a soap pump including a shaft, means actuated by said 70 shaft for reciprocating the pump piston, a disk on said shaft, a swinging nozzle on said pump, a lever provided with a longitudinal slot in one end, a pin on said disk extending into said slot, a link connecting 75 the other end of said lever and said nozzle, and means for driving the shaft in synchronism with said conveyor to operate the pump piston and swing said nozzle so as to follow each mould on the moving conveyor 80 until it fills the mould with soap.

In testimony whereof we affix our signatures.

REINHOLD H. GRIPP.
JOSEPH PYGEORGE.
